TWO-COMPARTMENT COIN-CONTROLLED VENDING-MACHINE.

1,076,769.

Specification of Letters Patent.

Patented Oct. 28, 1913.

Application filed September 3, 1912. Serial No. 718,220.

To all whom it may concern:

Be it known that we, SAMUEL J. KELLY and JOHN A. WEBSTER, citizens of the United States, and residents, respectively, 5 of White Plains, in the county of Westchester, State of New York, and Rutherford, in the county of Bergen, State of New Jersey, have invented certain new and useful Improvements in Two-Compartment Coin- 10 Controlled Vending-Machines, of which the following is a specification.

Our invention relates to coin-controlled vending machines of the so-called single-action type in which each magazine or compartment is adapted to hold a package of goods, and has for its object the provision 15 of a two-compartment machine having a single operating member, arranged to carry the deposited coin into engagement with one or the other of two locking devices which 20 control a pair of slideable locking bolts or slides, one for each lid. These locking bolts are adapted to be actuated by a single pivoted lever which is operated by the deposited 25 ed coin.

In the accompanying drawings Figure 1 shows a cross-sectional front view of a machine embodying our invention, the section being taken substantially on line 1—1 of 30 Fig. 2; Fig. 2 is a longitudinal view in cross-section of Fig. 1; Fig. 3 is a cross-sectional plan view on line 3—3 of Fig. 2; Fig. 4 is a back view of the plate carrying the lid-locking slides and the common actuating lever; 35 and Fig. 5 is a cross-sectional view on line 5—5 of Fig. 4.

The receptacle 1 of the machine is provided with a longitudinal partition 2 to form the two compartments or magazines 3 and 4 for the vendable articles. These compartments are provided with lids 5 and 6, respectively, which are independent of each other. These lids are hinged on a rod 7 mounted in the sides of the receptacle 1. 40 The back plate of the receptacle is provided with extensions 8 by means of which the machine is secured to a suitable support, such as the back of a theater chair. The front wall of each magazine is preferably 45 provided with a reinforcing plate 9 which is cut away at 10 to accommodate the extension 11 of the lids. When the lids are 50 closed they rest at their forward end on the

top of the reinforcing plate 9, as shown in Fig. 2.

To the front wall of the receptacle 1 are secured plates 12 and 13. The inner plate 12 rests directly against the front wall of the receptacle, while the outer plate 13 forms the front panel of the finished machine. The plates 12 and 13 are recessed at their upper half to accommodate the plate 14 between them. The locking slides or bolts 15 for the lids are slidably mounted on the plate 14, by means of guide studs 16, 55 which enter the elongated slots 17 in the slides. The studs 16 are fixedly mounted on the plate 14. At their adjacent upper ends the slides 15 are provided with rearwardly extending lugs 18 arranged to project over 60 the extensions 11 of the lids, when the slides are in locking position, as clearly shown at the left of Fig. 3. The lugs 18 extend through slots 19 formed in the front plate of the receptacle 1 and the reinforcing 65 plate 9. The inner plate 12 is provided with a recess 20 to accommodate the slides 15. The front plate 13 is provided with a recess or chamber 21 into which lead the two coin-entrance slots 22 and 23. The coin-exit slot 24 leads from the bottom of the chamber 21. In the chamber 21 operates the coin-carrier 25, which consists of a disk provided with a pair of oppositely disposed coin recesses 26. The coin-carrier is rigidly connected to the 70 inner end of the hub or stub shaft 27 extending inwardly from the hand-operated knob 28. The plate 14 has pivoted thereto the lever 29 by means of the pin or stud 30. At its lower end, the lever 29 is provided 75 with a forward extension 31 which projects through an arc-shaped slot 32 in the plate 14 into the chamber 21 of the front plate 13, as best shown in Fig. 2. It will be observed that the extension 31 projects in the 80 plane of rotation of the coin-carrier 25, so that (hereinafter explained) the deposited coin may be conveyed by the carrier into engagement with said extension. With each of the lid locking slides 15 is associated a 85 locking member 33, which is slidably mounted in the chamber 21 of the front plate 13. Each of these locking members 33 is at its upper end provided with a lug 34 which extends through the vertical slot 35 of the 90 plate 14 into engagement with the projec- 95

tion 36 of the associated slide 15, when the member 33 is in normal or uppermost position. This locking engagement between each slide 15 and its locking member 33, is shown at the left of Fig. 1, from which it will be clear that as long as the lug 34 engages the extension 36, the lid-locking slide 15 is held in locking position. The locking members 33 are each provided with a vertical slot 37 in which operates an extension spring 38 to hold the member normally in upper-most or locking position. The springs 38, bear at their upper ends against the top of the slots 37, and at their lower ends against the lugs 39 mounted on the front of the plate 14. Each of the locking members 33 is provided with a coin-engaging portion 40, which extends into the path of movement of the coin on the carrier, so that the coin may be forced against said extension and draw the locking member downwardly into releasing position.

The operation of the various parts as thus far described will now be understood and may be stated as follows: Let us say that the purchaser desires the package in compartment 4, which is the right-hand compartment. He deposits the required coin into the slot 23 and turns the knob 28 toward the right. No matter in what position the coin-carrier may be when the coin is deposited, rotation of the coin carrier will bring one of the coin-recesses 26 into position to receive the deposited coin, which is held in operative position between the recess 26 and the curved wall 41 in the chamber 21. As the coin-carrier is rotated, the deposited coin is carried along the wall 41 until it strikes the projection 40 on the adjacent locking member 33. Further movement of the coin-carrier causes the coin to depress the locking member 33 into releasing position. The coin, which is indicated at C in Fig. 1, thereupon comes into engagement with the extension 31 of the operating lever 29 and rocks the lever in a clockwise direction, so that the upper end of the lever engages the inner edge of the right hand slide 15 and shifts the same into releasing position. This position of the slide 15 is shown at the right of Figs. 1 and 3. The extension 11 of each lid is cut away at 42 at a point where the locking extension 18 of the slide 15 will come into alignment with said cut away portion when the slide is in actuated position. Consequently, after the slide 15 has been shifted by the lever 29, the lid 6 is free to be opened. It is usual to provide a spring at the bottom of each chamber in machines of this class, so that as soon as the lid is released the spring thrusts the package upwardly and thereby opens the lid. As this is a common expedient, it has not been thought necessary to show it.

65 Should the purchaser desire a package from

compartment 3, which is the left compartment, he deposits the coin in the slot 22 and turns the knob 28 toward the left. This causes the coin to unlock the left-hand member 33 and associated slide 15, in the same manner as above described. After the coin C has actuated the lever 29, further movement of the coin-carrier forces the coin from between the extension 31 and the locking member 33, as shown in Fig. 1, into the coin-exit slot 24 where it is retained by the bar or bolt 43. To release the coin, the bolt 43 is withdrawn by means of a key inserted in slot 44 of the front plate 13, and adapted to actuate the tumblers 45 of the lock 46. As this feature forms no part of my present invention, I have not deemed it necessary to show and describe any specific form of lock and key for withdrawing the bolt 43.

The slides 15 are at their adjacent upper ends provided with forwardly extending lugs 47, which project through the horizontal slot 48 of the plate 14. The arrangement of the lugs 47 is such that when a slide 15 is in normal or in locking position, its lug 47 does not interfere with the passage of the coin through the associated coin-slot. This is clearly shown at the left of Fig. 1. However, when the slide is in actuated or releasing position, its lug 47 projects into the associated coin-slot, so as to positively prevent the insertion of a coin into that slot. The slot-closing position of the lug 47 is clearly shown at the right of Fig. 1. It will thus be seen that when a compartment is empty, no coin can be inserted into the corresponding coin-slot, whereby a careless customer is prevented from losing his coin. The slides 15 are passive and remain in their operated position. It therefore becomes necessary to restore them to their initial or locking position. This is done by means of a special key adapted to be inserted into the key slots 49 formed in the sides of the plate 13. Each of the slides 15 is at its outer edge provided with a forwardly extending lug 50, which projects through the horizontal slot 51 formed in the plate 14. The lugs 50 extend into the key slots 49, so that the inserted key engages the lugs and forces the slides 15 inwardly into normal position.

When, during the rotation of the coin-carrier, the coin is forced out of engagement with the locking member 33, after the corresponding slide has been moved into releasing position, said member is at once carried upwardly by the spring 38, so that the locking lug 34 engages the inner shoulder 36^a of the extension 36 on the slide. This locks the slide against return movement and consequently prevents relocking of the empty compartment by an unauthorized person. It is therefore necessary before the actuated slides can be restored, to depress the locking members 33 out of engagement with the ex-

tensions 36. This is done by means of the bars 52 which are slidably arranged in the recesses 53 extending downwardly from the key slots 49. Each of the bars 52 is at its lower end provided with an inwardly extending lug 54, adapted to engage the lug 55 on the locking member 33. Normally the bars 52 rest by gravity at the bottom of the recesses 53, as shown at the right of Fig. 1. When the members 33 are moved into elevated position, as shown on the left of Fig. 1, the lug 55 carries the associated bar 52 upwardly, so that the beveled outer end 56 of the bar 52 extends into the key slot 49. When therefore the key is inserted into this slot, the bar 52 is depressed to move the locking member 53 into releasing position, and as the key is pushed inwardly, it then comes into contact with the slide 15 and forces the latter into normal position. It is, of course, understood that this restoring of the slides 15 does not take place until after the attendant has replenished the machine, and when he holds the lids down in closed position.

Having thus described our invention, what we claim as new and desire to secure by Letters Patent, is:

1. In a coin-controlled vending machine, the combination of a casing provided with two compartments, an independent lid and coin-slot for each compartment, an independent locking slide or bolt for each lid, a common actuating lever pivoted centrally with respect to said locking slides and adapted to engage the same at its upper end to move one or the other of said slides into unlocking position, a rotatable coin-carrier adapted to be manually operated in either direction and arranged to receive the coin deposited in either coin-slot, and a lug at the lower end of said lever extending into the path of the coin on the carrier, whereby the lever is rocked to unlock one or the other of said lids when the carrier is rotated in one direction or the other.

2. In a coin-controlled vending machine, the combination of a casing provided with two compartments, an independent lid and coin-slot for each compartment, an independent locking slide or bolt for each lid, a common actuating lever pivoted centrally with respect to said locking slides and adapted to engage the same at its upper end to move one or the other of the said slides into unlocking position, an adjustable retaining device associated with each locking slide for normally holding the same against unlocking movement, a rotatable coin-carrier adapted to be manually operated in either direction and arranged to receive the coin deposited in either coin-slot, each retaining device having a portion extending into the path of the coin on the carrier, so that the coin forces the adjacent retaining device into releasing position, a lug at the lower end of said lever adapted to be actuated by the coin after the retaining device has been moved into releasing position, and a lug on each locking slide for obstructing the associated coin-slot against the entrance of a coin when the locking slide is in unlocking position.

device into releasing position, and a lug at the lower end of said lever adapted to be engaged by the coin after the retaining device has been moved into releasing position to cause operation of said lever.

3. In a coin-controlled vending machine, the combination of a casing provided with two compartments, an independent lid and coin-slot for each compartment, an independent locking slide or bolt for each lid, a common actuating lever pivoted centrally with respect to said locking slides and adapted to engage the same at its upper end to move one or the other of said slides into unlocking position, a rotatable coin-carrier adapted to be manually operated in either direction and arranged to receive the coin deposited in either coin-slot, a lug at the lower end of said lever extending into the path of the coin on the carrier, whereby the lever is rocked to unlock one or the other of said lids when the carrier is rotated in one direction or the other, and a lug on each locking slide for obstructing the associated coin-slot against the entrance of a coin when the locking slide is in unlocking position.

4. In a coin-controlled vending machine, the combination of a casing provided with two compartments, an independent lid and coin-slot for each compartment, an independent locking slide or bolt for each lid, a common actuating lever pivoted centrally with respect to said locking slides and adapted to engage the same at its upper end to move one or the other of the said slides into unlocking position, an adjustable retaining device associated with each locking slide for normally holding the same against unlocking movement, a rotatable coin-carrier adapted to be manually operated in either direction and arranged to receive the coin deposited in either coin-slot, each retaining device having a portion extending into the path of the coin on the carrier, so that the coin forces the adjacent retaining device into releasing position, a lug at the lower end of said lever adapted to be actuated by the coin after the retaining device has been moved into releasing position, and a lug on each locking slide for obstructing the associated coin-slot against the entrance of a coin when the locking slide is in unlocking position.

5. In a coin-controlled vending machine, the combination of a casing provided with two compartments, an independent lid and coin-slot for each compartment, an independent locking slide or bolt for each lid, a common actuating lever pivoted centrally with respect to said locking slides and adapted to engage the same at its upper end to move one or the other of the said slides into unlocking position, an adjustable retaining device associated with each locking slide for normally holding the same

against unlocking movement, a rotatable coin-carrier adapted to be manually operated in either direction and arranged to receive the coin deposited in either coin-slot, 5 each retaining device having a portion extending into the path of the coin on the carrier, so that the coin forces the adjacent retaining device into releasing position, a lug at the lower end of said lever adapted 10 to be engaged by the coin to cause operation of the lever after the retaining device has been moved into releasing position, and a key-controlled restoring member associated with each retaining device for 15 storing the same to normal or retaining position.

6. In a coin-controlled vending machine, the combination of a casing provided with two compartments, an independent lid for 20 each compartment, a locking slide or bolt for each lid, a common actuating lever pivoted centrally with respect to said locking slides, the upper end of said lever extending between said slides to shift one or the other 25 into releasing position when the lever is actuated, and a rotatable coin-carrier adapted to cause operation of said lever through the medium of the deposited coin.

7. In a coin-controlled vending machine, 30 the combination of a casing provided with two compartments, an independent lid for each compartment, a locking slide or bolt for each lid, a common actuating lever pivoted centrally with respect to said locking slides, the upper end of said lever extending between said slides to shift one or 35 the other into releasing position when the lever is actuated, a lug at the lower end of said lever, and means for carrying the deposited coin against said lug to operate said lever one way or the other.

8. In a coin-controlled vending machine, the combination of a casing provided with two compartments, an independent lid and 45 coin-slot for each compartment, an independent slidable locking member for each lid, a pivoted lever adapted to engage one or the other of said members to move the same into locking position, and

means for carrying the deposited coin against 50 said lever to operate the same one way or the other.

9. In a coin-controlled vending machine, the combination of a casing provided with two compartments, an independent lid for 55 each compartment, an independent locking slide or bolt for each lid, a common actuating lever pivoted centrally with respect to said slides and adapted to engage the same at its upper end to move one or the other 60 of said slides into one locking position, and means for carrying the deposited coin against the lower end of said lever to operate the same one way or the other.

10. In a coin-controlled vending machine, 65 having a magazine or compartment, a lid for said compartment, a slidable locking member for said lid, a lug on said member adapted to engage said lid to hold the same locked, coin-controlled mechanism for moving said member into unlocking position, a coin-slot or guide leading to said mechanism, and a second lug on said locking member arranged to project into said coin-slot 70 when said member is in unlocking position. 75

11. In a coin-controlled vending machine having a magazine or compartment, a lid for said compartment, a locking member for said lid, means for normally retaining said member in locking position, coin-controlled 80 mechanism for first moving said retaining means into releasing position and then operating said locking member into unlocking position, said retaining means being adapted to automatically lock said member in unlocking position, and key-controlled means whereby said retaining member is first moved into normal or locking position and said locking member then moved into normal or locking position. 85

In witness whereof, we hereunto subscribe our names this 27th day of August, 90 1912.
